UNITED STATES PATENT OFFICE.

WILLIAM R. DALES, OF PHILADELPHIA, PENNSYLVANIA.

HAT-RETAINING DEVICE.

1,305,694.

Specification of Letters Patent. Patented June 3, 1919.

Application filed March 26, 1918. Serial No. 224,739.

To all whom it may concern:

Be it known that I, WILLIAM R. DALES, a citizen of the United States, residing at Philadelphia, in the county of Philadelphia and State of Pennsylvania, have invented 5 certain new and useful Improvements in Hat-Retaining Devices, of which the following is a specification.

The object of my invention is to provide 10 a novel, simple and efficient hat retaining device by means of which a hat may be held upon the head of the wearer thereof against the action of the wind and other forces tending to displace it, and by means of which a 15 cushioning effect between the hat and the head of the wearer may be produced so that the hat may be worn with ease and comfort.

With this and related objects in view, my 20 invented device consists of the elements and the combinations of them hereinafter described and claimed.

In the accompanying drawings, illustrating 25 my invention,

Figure 1 is a face view of my improved retaining device.

Fig. 2 is a bottom view of a hat having the device applied thereto.

Fig. 3 is a longitudinal section through 30 the hat with the device therein, on line 3—3 of Fig. 2.

Fig. 4 is a transverse section through the hat with the device therein, on line 4—4 of Fig. 2.

Referring to the drawings, 5 designates 35 the body of a hat and 6 a sweat band which extends around the inside of the hat body and has its lower edge portion attached thereto in the usual well known manner.

My retaining device is inserted between 40 the hat body 5 and the sweat band 6, preferably at the front of the hat, and it is formed of a single piece of spring wire bent to bring its end portions adjacent to each other and to form a loop, as clearly illustrated in 45 Fig. 1.

Included in the loop thus formed are upper and lower spaced members 7 and 8, respectively, and arms 9 which connect the members 7 and 8 at the respective ends thereof and which extend outwardly therefrom.

The members 7 and 8 have spaced bearing parts 10 and 11, respectively, and intermediate bearing parts 12 and 13, respectively. The spaced bearing parts 10 and 11 55 are adapted to engage the hat body 5, and the intermediate bearing parts 12 and 13

are adapted to engage the sweat band 6 and hold it normally spaced from the hat body, as shown in Figs. 2 and 3. The arms 9 may rest normally in contact with both 60 the hat body 5 and the sweat band 6.

The upper member 7 is formed by the lapping end portions of the wire which forms the device, the said end portions being twisted one around the other, at 14, as illustrated, at the respective ends of the member 7 to connect the said end portions in a manner to permit them to slide longitudinally 65 relatively to each other for a purpose hereinafter explained.

The end portions of the wire terminate in pointed prongs 15 which project outwardly from the twisted portions 14 thereof and which penetrate the sweat band 6 and thus prevent displacement of the device. One 70 prong 15 is made slightly longer than the other, so that when the device is applied to the sweat band 6, the long prong 15 is first projected through the sweat band 6 and then the long prong is drawn back while the short 75 prong 15 is projected through the sweat band. Thus the short prong may be inserted without liability of withdrawing the long prong from engagement with the sweat band. The free ends of the prongs 15 are 80 turned inwardly so as not to injure the head 85 of the wearer.

When the device is in place in the hat, as shown in Figs. 2, 3 and 4 it is confined entirely between the hat body 5 and the sweat 90 band 6, excepting the ends of the prongs 15 which hug the sweat band so closely that the wearer of the device is not conscious of their presence.

The device may be readily applied to the 95 hat by inserting it between the hat body 5 and the sweat band 6 and then inserting the prongs 15 into the sweat band, as previously described; and the device may be readily removed from the hat when desired by a 100 reversal of this operation.

When the device is applied to the hat as shown in Figs. 2, 3 and 4, and the hat is placed upon the head of the wearer, the central portions of the members 7 and 8 are 105 sprung from their normal position toward the hat body 5, and, afterward, as they tend to resume their normal position, they press against the head of the wearer with a cushioning effect and prevent accidental 110 displacement of the hat; and, in addition to this, they prevent the adjacent stiff portion

of the hat body from pressing against the forehead of the wearer and thus obviate the discomfort otherwise occasioned thereby.

The springing of the members 7 and 8 toward the hat body 5 tends to spring the free ends of the arms 9 inwardly in a manner to press the sweat band 6 gently against the sides of the head of the wearer and thus assist in preventing accidental displacement of the hat. When the member 7 is sprung inwardly, the lapping end portions of the wire forming it will yield by sliding longitudinally relatively to each other, as previously mentioned.

The pressure of the head of the wearer against the members 7 and 8 through the sweat band 6 forms a slight groove in that portion of the sweat band into which the forehead of the wearer may bulge slightly and thereby act as a means to prevent displacement of the hat. Further, the formation of this groove causes the sweat band to act as a suction cup to retain the hat in place as any force tends to accidentally displace it.

The lower portions of the arms 9 are flared upwardly, as illustrated, to permit the device to easily adapt itself to the head when the hat is placed thereon.

I claim:—

- 30 1. The combination with a hat body having a sweat band attached thereto, of a spring retaining device inserted between the body of the hat and the sweat band and having two spaced bearing parts engaging the body of the hat and a part intermediate said spaced bearing parts engaging the sweat band and held normally spaced from the hat body by said spaced bearing parts.
- 35 2. The combination with a hat body having a sweat band attached thereto, of a spring retaining device inserted between the hat body and the sweat band and comprising two spaced members connected at their ends, each member having two spaced bearing parts engaging the body of the hat and a part intermediate said spaced bearing parts engaging the sweat band and held normally spaced from the hat body by said spaced bearing parts.
- 40 3. The combination with a hat body having a sweat band attached thereto, of a

spring retaining device inserted between the body of the hat and the sweat band and having two spaced bearing parts engaging the body of the hat and a part intermediate said spaced bearing parts engaging the sweat band and held normally spaced from the hat body by said spaced bearing parts, and having an arm extending outwardly from one of said spaced bearing parts and adapted to be forced inwardly against the sweat band when said intermediate bearing part is pressed toward the hat body.

4. The combination with a hat body having a sweat band attached thereto, of a retaining device formed of a single piece of spring wire having its end portions connected and being bent to form an open loop having two spaced members, each member having two spaced bearing parts engaging the body of the hat and an intermediate bearing part engaging the sweat band and held normally spaced from the hat body by said spaced bearing parts.

5. The combination with a hat body having a sweat band attached thereto, of a retaining device formed of a single piece of spring wire having its end portions slidably connected and being bent to form an open loop having two spaced members, each member having two spaced bearing parts engaging the body of the hat and an intermediate bearing part engaging the sweat band and held normally spaced from the hat body by said spaced bearing parts.

6. The combination with a hat body having a sweat band attached thereto, of a retaining device formed of a single piece of spring wire having its end portions connected and being bent to form an open loop having two spaced members, each member having two spaced bearing parts engaging the body of the hat and an intermediate bearing part engaging the sweat band and held normally spaced from the hat body by said spaced bearing parts, and said end portions of the wire terminating in prongs which face in different directions and penetrate the sweat band and hold the device in place.

In testimony whereof I affix my signature hereto.

WILLIAM R. DALES.
